**RESERVOIR HANDLE FOR FOUNTAIN BRUSH
HAVING PISTON MEANS FOR FILLING
AND DISPENSING**

Ludwig F. Perwas, New York, N. Y.

Application May 1, 1945, Serial No. 591,244

3 Claims. (Cl. 222—128)

1

My present invention, in its broad aspect, has reference to improvements in fountain tooth brushes wherein a shaft is employed and a piston which is detachable from the shaft. The shaft has a valve-like end adjacent to a head and which in the passive condition of my tooth brush prevents passage of dentifrice to the brush bristles, and which is adapted to be connected with the piston, and the shaft reciprocated in the active condition of my toothbrush either to refill the dentifrice reservoir or discharge dentifrice from the reservoir to the bristles. Other features of my invention are: (1) the provision of improved air venting means, (2) the provision of an improved arrangement of knurled nut to rotate the shaft to engage it in the inactive position with the dentifrice channel to the bristles sealed and the shaft disengaged, (3) the provision of a novel and improved piston which in the inactive position is disconnected from the shaft, (4) the provision of removable bristles carrying disks for the bristle tufts whereby bristle tufts may be removed and replaced, (5) the provision of improved means for detachably connecting the brush head and shank with the handle having the dentifrice reservoir, (6) the provision of improved latches for the cap, and (7) the provision of an improved brush head and shank with a dentifrice channel leading to the bristles.

My above novel and improved structure as briefly outlined produces a simple, sturdy, dependable and efficient fountain tooth brush wherein the dentifrice is contained in the handle for dispensing as occasion requires, and which will not leak when not in use and which may be conveniently carried in a hand bag or in the pocket.

Other and equally important objects and advantages of my invention will be apparent from the following description and drawings, and it is pointed out that changes in form, size, shape, materials, and construction and arrangement of parts is permissible and within the purview of my broad inventive concept, and the scope of the appended claims.

In the drawings, wherein I have illustrated a preferred form of my invention:

Figure 1 is a longitudinal section showing the parts in passive position:

Figure 2 is a longitudinal section with the tooth brush assembly turned 90° from Figure 1;

Figure 3 is a detail longitudinal section showing the operating shaft refracted and connected

ing the operating shaft retracted and connected with the piston, the spring compressed, and the dentifrice passage to the brush head opened;

2

Figure 4 is a detail longitudinal section showing the piston and shaft being advanced to discharge dentifrice.

Figure 5 is a section on the line 5-5 of Figure 1.

Figure 6 is a bottom end view;

Figure 7 is a section on the line 1—1 of Figure 1;

Figure 9 is a perspective view of the disklike head, tapered, valve-like end, threaded sleeve, and operating rod shank with air vent opening; 15. Figure 10 is an enlarged section of a modified form of cap latch;

Figure 11 is a face view of the modified cap latch;

Figure 12 is a section on the line 12—12 of Figure 10, and

Figure 13 is an enlarged fragmentary section of the beveled knurled nut shown in Figures 1 and 2.

In the drawings, wherein like characters of reference are used to designate like or similar parts:

The numeral 1 designates my brush head, and 2 the shank, a passage or channel 3 is formed in

the brush head and shank, and communicates

through ports 4 in the bristle disks 5 with the bristle tufts 6. The bristle disks are threaded as at 7 to be detachably engaged in the brush head 1. The shank is threaded as at 8 to be engaged in the end or head 9 of the handle 10. A cap-like member 11 is cemented over the end and about end flanges 12 beneath which is a beveled knurled nut 13, the edges of which extend through slots and beyond the surface of the cap and end to be grasped and turned to detach the brush head shank 2 with which it is threadedly engaged. The channel 3 communicates with an opening 14 in the end 9 of the handle 10 which is restricted to form a beveled annular shoulder 15 constituting a valve-seat as will hereinafter appear. At each side of the end 9 are threaded bores 15 in which are threaded the sleeves 16. Each sleeve

houses a spring 17, a washer 18 and a ball 19, which is urged outwardly by the spring 17 but is prevented from being disengaged from the sleeve by an annular lip 20 about the outer edge of the sleeve. The balls 19 constitute latches for engaging in depressions 21 in the cap 22 to detachably hold the cap in place on the handle. As shown in Figures 10, 11 and 12, the end may have a slot 23 on each side with an inclined end 24 to receive the beveled end 25 of a plate 26, the

opposite end of which is held in place by a screw 27. Each plate has a beveled opening 28 to engage the sides of a conical latching member 29 which is pressed outwardly by a spring 30 in the bore 31 in the end and serves a purpose identical with the balls 19 to detachably latch the cap 22 in place.

The handle 10 is oval in cross-section and hollow to provide a dentifrice receptacle 32. An end part or plug 33 closes the opposite end of the handle and seats within its side walls. This part 33 has a central bore 34 which is enlarged at 35 and threaded as at 36 and leads into a circular depression 37 the side walls of which are slotted at 38.

An operating shaft or piston rod 39 fits through the bore 34 and is longitudinally slotted as at 40 to provide an air vent. The shaft is slidably and rotatably mounted and its upper end is pointed as at 41 to form a valve engaging the seat 11' on the end of the handle. The valve part 41 has a packing 42 and a disk-like head or valve 43 is mounted on the shaft back of the valve which has a beveled edge 44. Back of the head is an enlarged cylindrical threaded collar 45—see Figures 8 and 9. In the passive position of the parts of my device, the head 43 bears against the end 9 and the valve 41 rests on seat 11' to close the channel 3 to prevent leakage of dentifrice from the reservoir into the brush head.

A loose piston pump 46 having packing rings 47 is carried in the reservoir, and has a beveled edge 48 and a deep annular groove 49 receiving the spring 50, the opposite end of which seats in an annular groove 51 in the under side of the head 43. The piston has a threaded bore 51a and normally rests against the end part 33 when the parts are passive as in Figures 1 and 2.

At the opposite end of the shaft 39 is a knurled nut 52, an enlarged collar 53 having radial ribs 54 and a threaded part or plug 55. A knurled nut 56 is carried in the depression 37 of the end part 33. The brush head is placed in the supply of dentifrice and the dentifrice is drawn through the head, channel 3, and opening 14 in the end 9, and into the receptacle 32 in the handle, that is the dentifrice is simply sucked into the receptacle. In this operation the piston rod 39 and head 43 are drawn outwardly by the knurled nut 52 and the threaded part 45 threaded into the sleeve in the piston. The piston is then forced inwardly as the brush head is placed in the dentifrice and as the piston is drawn outwardly to the position shown in Fig. 3 the dentifrice is drawn into the opening 32 in the handle to fill the handle. The shaft 39 is then turned in the opposite direction to remove the thread 45 from the collar of the piston and the piston rod is moved inwardly with the member 41 coaxing with the seat 11' to close the passage from the handle to the brush head. The shaft is then pushed in and is urged by spring 50 until valve 41 engages seat 11' and the head 43 bears against the end 9 to seal the receptacle as shown in Figures 1 and 2, in which position the threaded part 55 is engaged with the end 33. To discharge or dispense dentifrice to the bristles, the nut 56 is rotated to release the shaft 39 which is retracted to engage the threaded collar 45 with the threaded bore 51a of the piston 46 and is accessible through slots 38, and is internally bored and keyed to engage collar 53. In the passive position, the threaded part 55 is engaged with the threaded part 36 of the end 33, and the knurled nut 52 is in an opening in the cap 57 which is held in place on the

end by screws 58. With the parts assembled as shown in Figs. 1 and 2 the ribs 54 coat with the knurled nut 56 whereby the shaft may be rotated with the end nut 52 in the recess in the member 57. Suitable packing 59 is located in the enlarged part 35 of the bore. To fill the receptacle 32 with dentifrice, the nut 56 is rotated to release the threaded part 55 of the shaft from the end 33. The nut 52 is then grasped and the shaft 10 39 retracted as shown in Figure 3 (air being exhausted through vent 40). The beveled edge 44 of the head 43 seats on the beveled edge 48 of the piston. The valve 41 is withdrawn from its seat 11' and opening 14 and channel 3 are open for passage of dentifrice to the bristles. The shaft is moved in and out until sufficient dentifrice is dispensed to the bristles, whereupon the tooth brush is ready for use and the shaft is returned to its passive position of Figure 1.

From the foregoing, it is believed that the operation and advantages of my invention will be apparent, but it is again pointed out that interpretation of its scope should only be conclusive when made in the light of the subjoined claims.

I claim:

1. In a fountain toothbrush, the combination which comprises a hollow tubular handle, oval shape in cross section, having an open outer end and a head having a centrally disposed longitudinally positioned opening therethrough, an oval shaped plug positioned in the open end of the handle and having a longitudinally disposed opening therethrough with a recess in the outer end and positioned around the said opening therethrough, an oval shaped pump piston slidably mounted in the handle and having a longitudinally disposed opening therethrough aligned with the opening through the plug and having an internally threaded hub in the center thereof with a valve seat in the inner end and spaced from the hub, a piston rod extended through the piston and plug having a valve on the inner end positioned to coat with the valve seat of the piston and also having a threaded boss thereon spaced from the valve and positioned to screw into the threaded hub of the piston, a spring on the piston rod between the piston and valve, said valve having a valve element thereon positioned to close the opening through the head of the handle, and a finger gripping nut on the outer end of the piston rod for screwing the threaded boss of the piston rod into the threaded hub of the piston and also for reciprocating the piston to provide a pump.

2. In a fountain toothbrush, the combination which comprises a hollow tubular handle, oval shape in cross section, having an open outer end and a head having a centrally disposed longitudinally positioned opening therethrough, an oval shaped plug positioned in the open end of the handle and having a longitudinally disposed opening therethrough with a recess in the outer end and positioned around the said opening therethrough, an oval shaped pump piston slidably mounted in the handle and having a longitudinally disposed opening therethrough aligned with the opening through the plug and having an internally threaded hub in the center thereof with a valve seat in the inner end and spaced from the hub, a piston rod extended through the piston and plug having a valve on the inner end positioned to coat with the valve seat of the piston and also having a threaded boss thereon spaced from the valve and positioned to

screw into the threaded hub of the piston, a spring on the piston rod between the piston and valve, said valve having a valve element thereon positioned to close the opening through the head of the handle, a finger gripping nut on the outer end of the piston rod for screwing the threaded boss of the piston rod into the threaded hub of the piston and also for reciprocating the piston to provide a pump, said nut of the piston rod having a ribbed collar on the piston rod side thereof, and a nut positioned on the collar and having slots therein for receiving the ribs of the collar for rotating the collar and piston rod.

3. In a fountain toothbrush, the combination which comprises a hollow tubular handle, oval shape in cross section, having an open outer end and a head having a centrally disposed longitudinally positioned opening therethrough, an oval shaped plug positioned in the open end of the handle and having a longitudinally disposed opening therethrough with a recess in the outer end and positioned around the said opening therethrough, an oval shaped pump piston slidably mounted in the handle and having a longitudinally disposed opening therethrough aligned with the opening through the plug and having an internally threaded hub in the center thereof with a valve seat in the inner end and spaced from the hub, a piston rod extended through the piston and plug having a valve on the inner end positioned to coact with the valve seat of the piston and also having a threaded boss thereon spaced from the valve and positioned to screw into the threaded hub of the piston, a spring on

5
